UNITED STATES PATENT OFFICE.

MASON B. GIBERSON, OF DETROIT, MICHIGAN, ASSIGNOR TO MONARCH STEEL CASTINGS COMPANY, OF DETROIT, MICHIGAN, A CORPORATION OF MICHIGAN.

DRAFT-RIGGING.

1,235,023.

Specification of Letters Patent. Patented July 31, 1917.

Application filed March 30, 1914. Serial No. 828,379.

To all whom it may concern:

Be it known that I, MASON B. GIBERSON, a citizen of the United States of America, residing at Detroit, in the county of Wayne 5 and State of Michigan, have invented certain new and useful Improvements in Draft-Riggings, of which the following is a specification, reference being had therein to the accompanying drawings.

10 The invention relates to draft riggings for railway cars, and has particular reference to the means of connection with the coupler shank. It is the primary object of the invention to obtain a construction in 15 which a strong connection is always maintained without the necessity for accurate fitting of the parts.

In the drawings:

Figure 1 is a plan view partly in section; 20 Fig. 2 is an end elevation; and Fig. 3 is a side elevation partly in section.

Figs. 4, 5 and 6 represent the members detached.

25 A is the shank of the car coupler and B is the draft frame connected to said shank and for engaging the resilient buffers. This frame, as shown, is in the form of a yoke, the opposite sides of which are spaced for

30 the reception of the buffer springs which are used in connection with suitable abutments (not shown). E is a head at the inner end of the shank A having shoulders F formed thereon adapted to engage hooks 35 G formed at the ends of the yoke B, said hooks being reinforced at G'. H is a hood embracing the shank A and head E and also the ends of the strap B. This hood is provided with a slotted bearing I through

40 which a key J is inserted to couple the same to the shank A. The contacting portions of the hood H and the strap B are wedge-shaped, and the arrangement is such that when the key J is inserted in the slotted bearing I and shank A, the hood will be drawn up to wedge the hook ends of the yoke into full engagement with the shoulders F.

45 The construction just described is one 50 which is particularly advantageous because it is difficult to manufacture the parts to accurate sizes, and consequently there is

danger of an imperfect engagement between the hooks G of the yoke and the shoulders F. With my improved device, however, this is 55 impossible, as the engaging wedge surfaces K and L will always force the yoke against the head E of the coupler shank, so that the hooks G are fully engaged.

What I claim as my invention is,— 60

1. In a draft rigging for car couplers, the combination with a coupler shank and a shouldered head thereon, of a draft yoke provided with hooks for engaging the shoulders, a hood for embracing said yoke and shank, the hood and shank having contacting surfaces inclined relative to each other to provide a wedge engagement whereby said hood forces said hooks in full engagement with said shoulders, and means 70 for securing said hood from displacement.

2. In a car coupler draft rigging, the combination with the coupler shank and a shouldered head therefor, of a draft yoke embracing said head and provided with 75 hooks for engaging the shoulders thereof, a hood embracing said shank and yoke, having wedged bearings upon the yoke, and a key for securing said hood to said shank and holding said wedge bearings in engagement. 80

3. In a car coupler draft rigging, the combination with the coupler shank of a shouldered head therefor, a draft yoke embracing said head and provided with wedge-shaped end portions and hooks for engaging said shoulders, a hood embracing said yoke and shank having complementary wedge bearings, and a key for securing said hood to said shank and holding said wedge 85 bearings in engagement.

4. A yoke for railway draft riggings which comprises a yoke proper having two spaced arms, the free ends of which are provided with shoulders to engage the upper 95 and lower shoulders of an M. C. B. draw bar, the upper and lower faces of said ends being respectively upwardly and downwardly inclined, and a band encircling and slidably along said arms and having its upper and lower walls inclined to correspond and fit with said inclined faces of the ends. 100

5. In a draft rigging for car couplers,

the combination with the coupler shank, of a draft yoke embracing said shank, a hood embracing the engaging portions of said shank and yoke, a wedging surface on said yoke, and a corresponding coöperating inclined surface on said hood whereby the former is clamped to said coupler shank,

In testimony whereof I affix my signature in presence of two witnesses.

MASON B. GIBERSON.
